CLAIM

The ornamental design for a cart as shown and described.

DESCRIPTION

FIG. 1 is a top-front-left perspective view of a cart according to the claimed design.

FIG. 2 is a top-rear-right perspective view of the cart.

FIG. 3 is a bottom-rear-left perspective view of the cart.

FIG. 4 is a bottom-front-right perspective view of the cart.

FIG. 5 is a front view of the cart.

FIG. 6 is a rear view of the cart.

FIG. 7 is a top view of the cart.

FIG. 8 is a bottom view of the cart.

FIG. 9 is a right side view of the cart; and,

FIG. 10 is a left side view of the cart.

The broken lines in the drawings illustrate portions of the cart that form no part of the claimed design.

1 Claim, 10 Drawing Sheets
